HOSIERY PACKAGE

Edward Gustave Jacobsson, New York, N. Y., assignor to Mojud Hosiery Co., Inc., Long Island City, N. Y., a corporation of Delaware

Application July 30, 1953, Serial No. 26,189

Term of patent 14 years

(Cl. D80—5)

To all whom it may concern:

Be it known that I, Edward Gustave Jacobsson, a citizen of the United States, residing at the city, county, and State of New York, have invented a new, original, and ornamental Design for Hosiery Package, of which the following is a specification, reference being had to the accompanying drawing, forming part thereof, wherein:

I claim:

The ornamental design for a hosiery package, substantially as shown.
